US0D1028732S

(12) **United States Design Patent** (10) **Patent No.:** **US D1,028,732 S**
(45) **Date of Patent:** **** May 28, 2024**

(54) **BOTTLE**

- (71) Applicant: **The Procter & Gamble Company**, Cincinnati, OH (US)
- (72) Inventors: **Joseph Allen Berlepsch**, Hamilton, OH (US); **Timothy Hunn Tao Ling**, Blue Ash, OH (US); **Nolwenn Husson**, Geneva (CH); **Jan Wertel**, Berlin (DE); **Gernot Oberfell**, Munich (DE); **Markus Mau**, Munich (DE)
- (73) Assignee: **The Procter & Gamble Company**, Cincinnati, OH (US)

(**) Term: **15 Years**

(21) Appl. No.: **29/896,232**

(22) Filed: **Jun. 30, 2023**

Related U.S. Application Data

(63) Continuation of application No. 29/770,510, filed on Feb. 12, 2021, now Pat. No. Des. 996,220.

(30) **Foreign Application Priority Data**

- Aug. 14, 2020 (WO) WIPO97057
- (51) **LOC (14) Cl.** **09-01**
- (52) **U.S. Cl.**

Primary Examiner — Omeed Agilee

(74) *Attorney, Agent, or Firm* — Andrew J. Mueller

(57) **CLAIM**

The ornamental design for a bottle, as shown and described above.

DESCRIPTION

FIG. 1 is a perspective view of a first embodiment of a bottle;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a bottle;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

1 Claim, 10 Drawing Sheets
